FISH LURE

Charles H. Redman, St. Charles, Ill.

Application January 27, 1954, Serial No. 28,692

Term of patent 7 years

(Cl. D31—4)

To all whom it may concern:

Be it known that I, Charles H. Redman, a citizen of the United States and a resident of the city of St. Charles, in the county of Kane and State of Illinois, have invented a new, original, and ornamental Design for a Fish Lure, of which the following is a specification, reference being had to the accompanying drawings, forming part thereof.

Figure 1 is a side view, in elevation, of a fish lure, showing my new design;

Figure 2 is a top plan view of the fish lure;

Figure 3 is a bottom elevation view thereof; and,

Figure 4 is a vertical cross-sectional view taken along the line 4—4 of Figure 1.

I claim:

The ornamental design for a fish lure, as shown.
